UNITED STATES PATENT OFFICE.

HARRY U. MORTON, OF CHICAGO, ILLINOIS, ASSIGNOR TO MORTON MANUFACTURING CO., A CORPORATION OF ILLINOIS.

CAR DIAPHRAGM AND METHOD OF FORMING THE SAME.

Application filed November 29, 1926. Serial No. 151,290.

This invention relates to railway car diaphragm units and a method of producing the same from a single strip of belting of uniform width by merely providing the strip of material with a plurality of spaced transverse folds to form a top with inclined side sections terminating in integral leg sections.

It is an object of this invention to provide a vestibule diaphragm for railway cars and the like, said diaphragm being constructed by merely folding a strip of material of uniform width at spaced intervals at the middle portion of the strip to form a complete diaphragm including a top with integral legs.

It is also an object of this invention to provide a car diaphragm wherein a single strip of material of uniform width is adapted to be provided with a plurality of transverse folds which are pressed to form a top having integral legs into the upper portions of which drip eaves formed by the top folds project.

It is a further object of this invention to provide an improved method of producing a car vestibule diaphragm by simply cutting a strip of multi-ply cotton belting to a predetermined length and uniform width, after which the strip of material is provided with a plurality of transverse folds at the middle portion which folds are pounded or pressed to afford projecting eaves disposed within the channel groove of the diaphragm consisting of a top section with integral legs resulting from the peculiar folding and creasing of the strip of material.

It is furthermore an object of this invention to provide a car vestibule diaphragm of the accordion-plaited type constructed of a single strip of material of uniform width either to form a diaphragm of either a single or a multiple fold construction, with the multiple fold diaphragms having the diaphragm units thereof provided with stiffeners within the bight beads which integrally connect the diaphragm units.

It is an important object of this invention to provide a railway car vestibule diaphragm, each of the units of which are of improved simplified construction wherein a pair of U-cross-sectioned diaphragm legs have the upper portions integrally connected with a U-cross-sectioned top formed by providing a plurality of transverse folds which are pressed to form dripped eaves

which project into the channel grooves of said legs to shed water, cinders, and other material dropping into the top downwardly and outwardly away from the diaphragm legs which are thereby protected.

Other and further important objects of this invention will be apparent from the disclosures in the specification and the accompanying drawings.

This invention (in a preferred form) is illustrated in the drawings and hereinafter more fully described.

On the drawings:

Figure 1 is a side elevation of a single unit of an improved railway car vestibule diaphragm embodying the principles of this invention.

Figure 2 is a side elevation thereof showing the eaves in dotted lines.

Figure 3 is an enlarged fragmentary detail section taken longitudinally through the middle portion of the top section on line III-III of Figure 1.

Figure 4 is an enlarged fragmentary transverse section of one of the diaphragm legs taken on line IV-IV of Figure 3.

Figure 5 is an enlarged fragmentary transverse section of the diaphragm top taken on line V-V of Figure 3.

Figure 6 is an enlarged fragmentary view of the middle portion of the diaphragm top looking upwardly on line VI-VI of Figure 3.

Figure 7 is a side elevation of a modified form of car diaphragm of the double fold type.

Figure 8 is an enlarged transverse section of the top of the double fold diaphragm illustrated in Figure 7.

As shown on the drawings:

The reference numeral 1 indicates a railway car vestibule face plate of the usual inverted U-shaped construction to which one end of an improved diaphragm unit is adapted to be rigidly secured by a suitable U-shaped metal strap or frame or other suitable means. The other side or edge of the improved car diaphragm unit is adapted to be secured to the end of a car by any suitable retaining means. The improved car diaphragm is of accordion-plaited construction and is adapted to be made of a plurality of units each of which embodies the principles of this invention. The diaphragm may be constructed of a single fold or of

multiple folds as desired. This invention relates to a simplified method whereby a diaphragm unit may be readily constructed without sewing or cutting, except as to length. The method consists of using a single strip of multi-ply cotton belting of uniform width, said strip of material being cut to a predetermined length after which the material is first folded transversely at its middle portion to provide a straight line crease 3 and an angled line crease 4 along which lines the material is folded and then creased by pounding or applying pressure to form a middle fold 5 to form a diaphragm top consisting of a pair of U-cross-sectioned top sections 6 which incline downwardly and outwardly from the middle or intermediate fold 5 disposed at the apex of the diaphragm top. The strip of material forming the diaphragm is also provided with two sets of creases positioned equi-distantly from opposite sides of the intermediate fold 5. Each of the side sets of creases comprises a straight line crease 7 and an angle line crease 8 which is deeper than the angled line crease 4. The side sets of creases 7 and 8 are pressed or pounded into shape to form side folds 9. The top sections 6 and the folds 5 and 9 cause the strip of material to assume a U-shaped cross section with the side folds 9 acting as a connecting medium between the top sections 6 and the end portions of the strip of material which form U-cross-sectioned parallel legs 10. The side folds 9 are so shaped that they project into the channel or U-shaped grooves formed by the legs 10 with said side folds adapted to serve as projecting eaves or chutes whereby any water, cinders, or other foreign elements which may be deposited in the trough formed by the inclined top sections will be permitted to run or slide downwardly out of the inclined top sections and be directed downwardly and outwardly away from the diaphragm legs thereby protecting said legs from the action of the water and cinders. The pitch of the top section 6 is such that material deposited in said sections will not lodge there, but will immediately be discharged by the action of gravity.

It will thus be seen that the multi-ply strip of cotton belting or other suitable material is of uniform width, cut to a predetermined length, and subsequently creased and folded at its middle portion and at equal distances from opposite sides thereof to form a middle or intermediate fold and a pair of said folds which are pressed or pounded into shape to cause the unitary strip of material to form a railway car vestibule diaphragm unit of U-shaped or channel cross section comprising a pair of integrally connected inclined top sections terminating in a pair of parallel legs to form a complete one piece diaphragm with the side folds at the outer ends of said

top sections projecting into the upper portions of the channel grooves of the diaphragm legs to form eaves for discharge chutes whereby water, cinders, or other material which may be deposited in the top sections will be discharged by gravity downwardly and outwardly away from the diaphragm legs.

Figures 7 and 8 of the drawings illustrate a modified form of railway car vestibule diaphragm of a multiple fold accordion-plaited type adapted to have one end of the diaphragm connected to a railway vestibule face plate 11 by means of a U-shaped metal strap or frame 12 and the other end of said diaphragm connected to the end of the railway car by any suitable retaining means. In this construction the multiple fold diaphragm is also constructed of a single strip of multi-ply cotton belting or other suitable material, said strip being of uniform width and cut to a predetermined length, folded longitudinally along the middle to form a central bead or hem 13 adapted to form a pocket in which a U-shaped metal stiffening frame or brace rod 14 is adapted to be inserted. The strip of material on each side of the bead 13 is creased at the middle portion and at equal distances from said middle portion similar to the arrangement illustrated and described in connection with Figure 3, to form an intermediate fold 15 and side folds 16, thereby shaping the material on both sides of the connecting bead 13 to form integrally connected diaphragm units comprising channel cross-sectioned inclined top section 17 terminating in parallel channel cross-sectioned legs 18.

It will thus be seen that a single strip of material of uniform width and of a predetermined length may be creased and folded to form a railway car vestibule diaphragm to form either a single fold diaphragm unit or a multiple fold diaphragm unit of one piece construction obviating stitching and the like in so far as the construction of a single fold diaphragm unit is concerned. In the multiple fold diaphragm construction the bead or hem 13 connecting the diaphragm units and enclosing a stiffening rod or frame of metal may be stitched to hold the stiffening frame 14 in place, or if preferred the stiffening frame 14 may be secured in the bead 13 by rivets, bolts, or any other suitable retaining means in which case the use of stitching is obviated.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. A railway car vestibule diaphragm unit

constructed of a single strip of material of uniform width cut to a predetermined length and creased and folded transversely intermediate its ends to form a top with inclined 5 top sections terminating in integral legs.

2. A railway car diaphragm constructed of a single piece of material creased and folded at intervals to form connected inclined top sections integral with a pair of 10 leg sections.

3. A car diaphragm constructed of a single strip of material of uniform width folded longitudinally to afford a connecting bead between diaphragm units by creasing 15 and folding the material on each side of the bead to form a top section integrally connecting leg sections, and stiffening means within said bead to afford a brace for the integrally connected diaphragm units.

20 4. A car diaphragm of the class described adapted to be constructed from a single strip of material of uniform width folded lon-

gitudinally to form a connecting bead, a stiffening frame in said bead, said material on opposite sides of the bead being transversely 25 creased and folded to form an intermediate fold and end folds to shape said material on each side of the bead to afford inclined top sections integrally connected to leg sections having the side folds projecting into the leg 30 sections to serve as discharge chutes for diverting materials deposited into the top sections outwardly away from said leg sections.

5. The method of constructing a railway car diaphragm unit consisting of creasing a strip of material of uniform width to form transverse folds and then pressing said folds 35 to cause the strip of material to shape itself into inclined top sections integrally connecting leg sections. 40

In testimony whereof I have hereunto subscribed my name.

HARRY U. MORTON.
